F. EICHLER, OF NEW LISBON, WISCONSIN.

Letters Patent No. 85,002, dated December 15, 1868.

IMPROVEMENT IN PORTABLE PUMPS.

The Schedule referred to in these Letters Patent and making part of the same.

To all whom it may concern:

Be it known that I, F. EICHLER, of New Lisbon, in the county of Juneau, and State of Wisconsin, have invented certain new and useful Improvements in Force-Pumps; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

In the drawings—

Figure 1 is a vertical cross-section through the centre, and

Figure 2 is a longitudinal vertical section.

My invention relates to a force-pump of peculiar construction, intended for household and farm-use, which can be easily operated by one man, and by him readily transported from place to place, as occasion requires.

My pump is constructed as follows:

A represents a strong rectangular box or reservoir, partially covered, intended to contain the water which is to be forced through and thrown from the pump.

Inside of this box I station a rectangular pump or valve-chest, B, considerably smaller than the box A, and which is secured by lugs or ears h h, bolted on its under side, to the stationary shaft C upon which it rocks or oscillates.

The valve-chest B, I construct of wood or other suitable material, and fasten it securely together by the metal frame g and bolts i i, and it is divided into three chambers, B¹, B², and B³, and these are provided with a series of valves, a, b, c, d, and a port or opening, e, connecting them one with another, and also with the exterior body of water in the reservoir A.

In the central chamber B², I place a piston, D, attached to the piston-rod E, which extends up through the stuffing-box f, and is attached to an eye or lug, j, on the end of the hand-lever F, which lever is pivoted at k to the stationary post G, attached to the covered portion of the box A, as shown in fig. 1.

The water enters the chest through the valves a and b alternately, and flows through into the chamber B³, from which it is forced up through pipe H, attached at the upper end

The chamber B³ is connected to chamber B² by the two valves c and d, one below and one above the piston, and chamber B² is connected to the chamber B¹ by the port e.

My pump being thus constructed, operates as follows:

The reservoir being filled, the lever is forced down, which will draw the piston up, when the valves b and c will close, and the water above the piston in the chamber B² will, as the chambers B¹ and B³ are filled, be forced through valve d into chamber B³, and thence out through the pipe H, and water will at the same time rush in through valves a, and fill the void in the chamber B² below the piston, as shown by the red arrows in fig. 2.

Upon the motion of the lever being reversed, the valves a and d will close, and the water below the piston will be forced through c into B³, displacing the water already there, and forcing it in turn through pipe H, the water in B¹ at the same time flowing over through e and filling the chamber above the piston, and being replaced by water flowing in through b from the reservoir A.

It will thus be seen that a continuous stream will be thrown from the pump without the use of the air-chamber, as usual, although it may be attached to prevent any jar when working the pump rapidly.

The object of pivoting the valve-chest is to allow of a lateral movement equal to that of the piston-rod, the upper end of which moves in an arc of a circle. When, for any purpose, it is desired to detach the valve-chest, it may be done by simply withdrawing shaft C and detaching the piston-rod from eye j, when the chest may be lifted from its place.

It is obvious that any suitable nozzle or pipe may be attached to pipe H, and that the under side of the chest may be so arranged as to permit the attachment of a pipe and thus draw water from a distance.

Thus I construct a pump, which, for farmers and residents of small villages, where there are no enginies, will be a great protection against fire, and for washing windows, irrigation, &c., will accomplish more, and that better than can be done by hand, which can be built at a small expense, and may be easily worked by one man, who can transport it from place to place, at will.

Having thus described my invention,

What I claim, is—

A portable force-pump, consisting of a reservoir or box, A, having hinged therein by lugs h, to a rod, C, a valve-chest with three separate chambers, B¹, B², and B³, connected by three valves, c, e, and d, all constructed as described, and arranged to be operated as set forth.

F. EICHLER.
